UNITED STATES PATENT OFFICE.

EMIL A. CUPPERS, OF NEW HAVEN, CONNECTICUT, ASSIGNOR TO SARGENT & CO., OF SAME PLACE.

DESIGN FOR COFFIN-HANDLE SOCKET.

SPECIFICATION forming part of Design No. 11,810, dated June 8, 1880.

Application filed May 10, 1880. Term of patent 7 years.

To all whom it may concern:

Be it known that I, EMIL A. CUPPERS, of New Haven, in the county of New Haven and State of Connecticut, have invented a new 5 Design for Coffin-Handle Sockets; and I do hereby declare the following, when taken in connection with the accompanying drawing and the letters of reference marked thereon, to be a full, clear, and exact description of the 10 same, and which said drawing constitutes part of this specification, and represents a face view.

This invention relates to a design for that part of the coffin-handle commonly called the "socket"—that is, that part by which the handle is secured to the coffin; and the invention 15 consists in the configuration and ornamentation of the socket, as shown in the accompanying illustration.

The general outline of the base is of rectangular form, with an enlargement at each angle. From each of two opposite angles ex-

tending inward toward the center is a fan-shaped ornamentation. At the center is the socket A or recess, within which the lever is hung, and surrounding this is a wreath of oval 25 form, represented as lying upon the fans and extending toward the other two angles, as shown in the accompanying illustration.

I claim—

The design for coffin-handle socket, consisting of the rectangular-shaped base, with a fan-shaped ornamentation extending inward from two opposite angles, with the representation of a wreath surrounding the center of the socket proper and resting on said fan-shaped ornamentation, as shown in the accompanying 30 35 illustration.

EMIL A. CUPPERS.
